UNITED STATES PATENT OFFICE.

BENJAMIN FRANKLIN POWELL, OF MANZANOLA, COLORADO.

HAY-STACKER.

No. 845,576.

Specification of Letters Patent.

Patented Feb. 26, 1907.

Application filed May 7, 1906. Serial No. 315,563.

To all whom it may concern:

Be it known that I, BENJAMIN FRANKLIN POWELL, a citizen of the United States, and a resident of Manzanola, in the county of 5 Otero and State of Colorado, have invented a new and Improved Hay-Stacker, of which the following is a full, clear, and exact description.

The purpose of the invention is to provide 10 a portable hay-stacking device in which a sled or hay-frame previously loaded upon the field is drawn up an incline and received upon a tipple of exceedingly simple, light, and durable construction and wherein when 15 the load is automatically dumped from the sled or frame by means of said tipple the empty sled or frame will slide down the incline to the ground of its own accord.

Another purpose of the invention is to 20 provide sleds or frames for gathering the hay particularly adapted to the improved stacker and which are low and flat, enabling them to be readily loaded and also rendering them light of draft, enabling the sleds to be readily 25 drawn over stubble, and, further, to so construct the sleds that when loaded and drawn to the stacker the hoist-ropes of the latter may be instantly applied thereto and operated.

30 The invention consists in the novel construction and combination of the several parts, as will be hereinafter fully set forth, and pointed out in the claims.

Reference is to be had to the accompanying 35 drawings, forming a part of this specification, in which similar characters of reference indicate corresponding parts in all the figures.

Figure 1 is a side elevation of the improved stacker, illustrating a loaded sled at 40 its base as connected with the hoist-ropes of the stacker. Fig. 2 is a plan view of the structure as shown in Fig. 1. Fig. 3 is a side elevation of a portion of the stacker, 45 showing the tipple in dumping position and also a sled in position on the tipple. Fig. 4 is a front elevation of the stacker. Fig. 5 is a plan view of the sled or hay-frame used in connection with the stacker; and Fig. 6 is a 50 front elevation of the said sled or a view looking at its dumping edge.

In the construction of the base parallel transverse runners 10 are employed, connected by sills 11. Uprights 12 are secured 55 to the rear runner, and shorter uprights 13 are attached to the forward runner, the up-

rights both at the front and at the rear being usually three in number, and corresponding uprights at the sides of the base are connected by said sills 11. The base is strengthened 60 by cross-braces 14, as is shown in Fig. 2. A cross-bar 15 is secured to the upper end portions of the rear uprights 12, and a second cross-bar 16 is secured to the upper ends of the forward uprights 13.

The frame just described is adapted to support skids, which skids are usually three in number and are arranged in parallelism and are inclined from their lower ends upward, extending both forwardly and rearwardly of the said frame. The outer skids are designated as A and A', and the intermediate skid as B, as is shown in Figs. 2 and 4. While the skids may be made in one piece, they are preferably constructed 75 in sections, as shown, each skid comprising an upper section 17, an intermediate section 18, and a lower section 19, which rests upon the ground. The upper and intermediate sections are connected by couplings 20 of 80 any approved character, but the lower sections 19 have a hinged connection 21 with the intermediate sections 18, and to that end the upper ends of the lower sections 19 are bifurcated to pivotally receive the corresponding 85 portions of the intermediate sections 18, as is best shown in Fig. 2.

A cross-bar 22 is provided as a rest for the lower portions of the intermediate sections of the skids, as is shown in Figs. 1 and 2, and 90 these cross-bars are secured to side braces 23, which are secured at their lower ends to the lower portions of the front standards 13 and to the intermediate sections 18 of the side skids A and A' adjacent to the lower ends of 95 said sections. Any desired number of cross-braces 24 is employed to strengthen the body-frame of the machine.

Braces 25 are located at the rear of the body-frame, one at each side. These braces 100 are attached to the side sills 11 and to the braces 24, which they may cross, and the side uprights 12 and said braces 25, which may properly be termed "supporting-arms," 105 extend from the base diagonally upward and rearward and connect with the upper end portions of the side skids A and A'. The side skids A and A' extend some distance beyond the rear cross-bar 15, as is best shown in Fig. 2; but the central skid B extends but 110 slightly beyond the said cross-bar.

A pivot-rod 26 is passed through the upper

end portions of the side skids A and A' and the upper ends of the supporting-arms 25, and at the desired point below the said pivot-rod 26 a transverse stop-bar 27 is secured to the supporting-arms 25.

In connection with the structure just described I employ a tipple C of peculiar construction, which tipple consists of side bars 28, a lower cross-bar 29, and corner-braces 30, the space between the opposite ends of the said side bars being entirely open. The free ends of the side bars 28 of the tipple are strengthened at each side by metal plates, (designated as 31 and 32,) and from each outer plate 32 a hook or a downwardly and outwardly curved arm 33 is made integral with the said plate 32, as is best shown in Fig. 3, and when the tipple C is in its normal or receiving position these hooks or curved arms 33 extend in direction of the lower or receiving end of the stacker.

Between the strengthening-plates 31 and 32 a pulley 34 is mounted in each side bar 28 of the tipple. It will be observed that the plates 31 and 32 serve to so strengthen the tipple where the pulleys 34 are located that when ropes to be hereinafter described are passed over the pulleys and are drawn upon the tipple will be strong enough to resist very severe strain. This tipple is located between the upper ends of the outer or side skids A and A' and is pivoted on the said pivot-rod 26, the rod passing through the tipple nearer its open than its closed end.

Draft ropes or cables 35 are passed over the pulleys 34 in the tipple, and normally one end portion of these ropes extends downward above the skids to the bottom forward portion of the structure, as is shown in Fig. 1, and the other end portions of the said ropes or cables 35 are passed over pulleys 36, located on the lower end portions of the rear uprights 12, and then the lower portions of the ropes or cables 35 are carried forward and are passed over pulleys 37, suitably mounted on the forward runners 10, as is best shown in Fig. 4. These ropes or cables 35 are provided with hooks and eyes or loops at their ends, as may be found most desirable.

In connection with the improved stacker sleds or hay-carrying frames D are employed. (Shown in detail in Figs. 5 and 6.) These sleds are flat, so that they can be readily drawn over stubble and so that they can be readily loaded, and the bottom portion of each sled D consists of a series of parallel slats connected by cross-bars 39, and at one longitudinal edge of said bottom a back structure 40 is formed, likewise of slats, but connected to the bottom by uprights 40^a, as is best shown in Fig. 6. In the further construction of a sled D hooks 41, two in number, are secured to convenient cross-bars 39 at the open side portion of the sled or that portion which is opposite the back 40.

When a sled is drawn over the ground to be loaded or to be carried when loaded to the stacker, draft-trees 42 of any suitable construction are connected with one end portion of the sled, as is shown in Fig. 5; but when the sled has been brought to the base of the skids A and A' and B it is turned around so that its open side will rest upon the skids, and its back 40 at such time will be on the ground, as is shown in Fig. 1. The draft-trees 42 are then unhitched from the sled and are attached to the forward lower ends of the draft cables or ropes 35, and the forward upper end portions of the said draft cables or ropes are secured to the sled by means of the hooks 41.

It may here be remarked that a rope 38 is attached to the cross-bar 29 of the tipple C, and this rope is usually carried loosely over the rear cross-bar 15 and down to the base, where its other end is secured.

In operation, as the team is driven from the stacker the sled is drawn up the skids until it is received upon the tipple C, and at about the time the open side of the sled engages the hooks or curved arms 33 the tipple will have been overbalanced and will have a downward and rearward inclination, (shown in Fig. 3,) which will cause its load to be dumped, and the hooks or arms 33 will effectively hold the sled on the tipple during the dumping operation. After the load has been discharged from the sled the rope 38 is drawn upon, and the tipple is drawn down until the sled engages with the side skids A and A', whereupon as the draft-rope is slackened the sled travels down the incline of the skids by its own weight. The rope 38 limits the upward movement of the connected end of the tipple, as well as serving to draw the said end downward after dumping, and when the tipple is in its normal or receiving position (shown in Fig. 1) the lower portion of the tipple will rest against the cross-bar 27, located below the pivot-point of the tipple, thus insuring the said tipple having the same inclination at all times after dumping.

When a stacker and sleds such as have been described are employed, the hay is handled only once by the pitchfork before it is deposited on the stack, which is of great advantage in handling alfalfa and clover-hay, since it prevents breaking and crushing of the hay and also loss of leaves.

Having thus described my invention, I claim as new and desire to secure by Letters Patent—

1. In hay-stackers, a series of inclined skids, a support for the same, a tipple pivotally mounted at the upper ends of the skids, which tipple consists of side bars connected at one end and having metal reinforcements at their opposite or free ends, pulleys within said bars at their reinforced ends and curved projections from the side portions of said

reinforced ends, hoist-ropes passed over said pulleys, and guide-pulleys for said ropes located on the support for the skids.

2. In a hay-stacker, the combination with 5 a supporting-frame, a series of skids carried by the said frame, having an inclination from their upper ends downward, all of the skids extending beyond the forward end of the frame, the two side skids only extending beyond the rear end of the frame, the said skids being constructed in sections, the lower sections having pivotal connections, of a tipple pivotally mounted between the rear extremities of the side skids, which tipple consists of side bars and a lower cross-bar, reinforcing-plates at the upper free ends of the side bars, a pulley located in each side bar between the reinforcing-plates, and a forwardly and downwardly curved hook extending from the reinforced face of each of the said side bars, a cable attached to the cross-bar of the tipple, being guided downward by the said frame, a hoist-rope passed over the pulleys in the tipple, extending from the upper portion of the skids downward, guide-pulleys carried by the said frame for the said hoist-ropes, and a stop carried by the frame for engagement by the lower end of the tipple when the latter is in its normal position.
3. In a hay-stacker, the combination with 15 a supporting-frame, a series of skids carried by the said frame, having an inclination from their upper ends downward, all of the skids extending beyond the forward end of the frame, the two side skids only extending

beyond the rear end of the frame, the said skids being constructed in sections, the lower sections having pivotal connections, of a tipple pivotally mounted between the rear extremities of the side skids, which tipple consists of side bars and a lower cross-bar, reinforcing-plates at the upper free ends of the side bars, a pulley located in each side bar between the reinforcing-plates, and a forwardly and downwardly curved hook extending from the reinforced face of each of the said side bars, a cable attached to the cross-bar of the tipple, being guided downward by the said frame, a hoist-rope passed over the pulleys in the tipple, extending from the upper portion of the skids downward, guide-pulleys carried by the said frame for the said hoist-ropes, a stop carried by the frame for engagement by the lower end of the tipple when the latter is in its normal position, and a sled 40 adapted to travel on the said skids and to be engaged by the said tipple, which sled consists of a flat body having a back structure extending therefrom at one of its longitudinal edges, and hooks located on the said body at 45 its open side edge, the upper stretches of the hoist-ropes having means for attachment to the said hooks.

In testimony whereof I have signed my name to this specification in the presence of 55 two subscribing witnesses.

BENJAMIN FRANKLIN POWELL.
